J. S. BOOTH

AUTOMOBILE RADIATOR

Filed March 5, 1924

James Scripps Booth ^{Inventor}

By Stuart C Barnes ^{Attorney}

Patented June 22, 1926.

Des. 70,398

UNITED STATES PATENT OFFICE.

JAMES SCRIPPS BOOTH, OF DETROIT, MICHIGAN.

DESIGN FOR AN AUTOMOBILE RADIATOR.

Application filed March 5, 1924. Serial No. 8,828. Term of patent 14 years.

To all whom it may concern:

Be it known that I, JAMES SCRIPPS BOOTH, a citizen of the United States, residing at Detroit, in the county of Wayne and State of Michigan, have invented a new, original, and ornamental Design for Automobile Radiators, of which the following is a specification, reference being had to the accompanying drawing, forming part thereof.

Fig. 1 is a front elevation of a radiator showing my new design.

Fig. 2 is a side elevation of the radiator showing my new design.

I claim:

The ornamental design for an automobile radiator as shown.

JAMES SCRIPPS BOOTH.
